UNITED STATES PATENT OFFICE.

SAMUEL FRIEDMAN, OF BROOKLYN, NEW YORK.

FUR SOFTENING AND CLEANING MACHINE.

Application filed September 9, 1921. Serial No. 499,483.

To all whom it may concern:

Be it known that I, SAMUEL FRIEDMAN, a citizen of the United States, and a resident of the city of New York, Evergreen, borough of Brooklyn, in the county of Kings and State of New York, have invented a new and Improved Fur Softening and Cleaning Machine, of which the following is a full, clear, and exact description.

10 The invention relates to furs and pelts and its object is to provide a new and improved machine more especially designed for softening and cleaning fur garments and fur skins in a very quick and effective manner and without danger of injury to the garment or to the fur skin.

Another object is to facilitate the placing of the garment or fur skins into the machine for softening and cleaning purposes and to 20 permit of removing the same therefrom after the softening and cleaning operation is completed.

Another object is to permit of readily separating the sawdust or similar loose material used as a cleaning medium from the garments or fur skins after the softening and cleaning thereof is finished.

Another object is to separate loose hairs from the sawdust to allow convenient and 30 immediate re-use of the sawdust.

Another object is to provide a fur softening and cleaning machine which is simple and durable in construction and composed of comparatively few parts not liable to get 35 easily out of order.

A practical embodiment of the invention is represented in the accompanying drawings forming a part of this specification, in which similar characters of reference indicate corresponding parts in all the views.

Figure 1 is a perspective view of the improved fur softening and cleaning machine;

Figure 2 is an enlarged cross section of the same;

Figure 3 is a sectional side elevation of the same on the line 3-3 of Figure 2;

Figure 4 is a cross section of part of the machine showing the gearing for driving the tumbling drum, the section being on the 50 line 4-4 of Figure 3;

Figure 5 is an enlarged sectional side elevation of the mounting for the rubbing device;

Figure 6 is a similar view of a modified 55 form of the same; and

Figure 7 is a perspective view of the pressing and rubbing device.

The improved fur softening and cleaning machine is mounted in a suitably constructed casing 10, preferably made of sheet metal, and provided at the front with a door opening 11 adapted to be opened and closed by a sliding door 12 mounted to slide exteriorly on the upper portion of the casing 10. Within the casing 10 is arranged a tumbling drum or barrel 15, preferably made of sheet metal, and having at the inner surface wooden heads 16 and wooden ledges 17 projecting inwardly from the inner surface of the rim 18 of the drum 15.

The ledges 17 are spaced equal distances apart, and between two of the ledges is arranged a door opening 20 adapted to be closed by a sliding door 21 mounted to slide exteriorly on the rim 18 of the drum 15, and similar to the sliding door 12. Within the door opening 20 in the rear of the door 21 when the latter is closed is arranged a screen 25 slightly spaced from the door 21 when the latter is closed.

The screen 25 is pivoted on the ledge 17 at the bottom of the door opening 20 to permit of swinging the said screen 25 outwardly into an open position through the door opening 11 at the time the doors 12 and 21 are in open position.

It will be noticed that when the parts are in this position a fur garment, a fur skin or a plurality of either may be placed into the drum 15 for softening and cleaning purposes or for removing the same therefrom through the door openings 20 and 11 after the softening and cleaning operation is repeated.

It will also be noted that through the door openings 11 and 20 sawdust or other similar loose cleaning material may be placed into the drum 15 to insure a thorough cleaning of the garment or fur skin as hereinafter more fully explained.

The drum 15 is preferably provided with a second door opening 30, preferably located diametrically opposite the door opening 20 and likewise controlled by a sliding door 31 mounted to slide on the exterior surface of the rim 18 of the drum 15. Within the door opening 30 is also arranged a screen 32 which may be either hinged or fixed permanently in the said door opening. The doors 21 and 31 are both opened whenever it is desired to discharge the sawdust, the dirt and loose hairs that may be in the drum 15.

from the said drum into the casing 10, as hereinafter more fully explained.

The drum 15 is provided with trunnions 40 and 41 journaled in suitable bearings 42 attached to brackets 43 fastened to the sides of the casing 10, and on the trunnion 41 is secured a gear wheel 45 in mesh with a pinion 46 secured on a shaft 47 journaled in a bracket 48 attached to the corresponding side of the casing 10. On the shaft 47 is secured a pulley 50 connected by a belt 51 with a pulley 52 secured on the shaft 53 of a motor 54 of any approved construction, preferably, however, of the electric type and mounted on the rear top portion of the casing 10. It will be noticed that when the motor 54 is running a rotary motion is transmitted by the gearing just described to the drum 15 to rotate the latter in the direction of the arrow indicated in Figure 2. A guard 55 preferably encloses the aforesaid gearing.

Within the drum 15 is arranged a pressing and rubbing device, preferably in the form of a roller 60 journaled in arms 61 pivotally connected at 62 with links 63 having trunnions 64 journaled in the trunnions 40 and 41. The trunnions 64 are preferably provided with split retaining rings 65 to hold the trunnions 64 against accidental displacement in the trunnions 40 and 41. The links 61 have their upper ends 66 projecting beyond the pivots 62 and the said upper ends 66 normally abut against stop pins 67 arranged on the links 73 thus normally holding the side arms 61 in angular position relative to the links 63, as plainly indicated in Figure 2. By the arrangement described the rubbing and pressing roller 60 extends in close proximity to the ledges 17 as the latter reach bottom positions and hence the said rubbing and pressing roller 60 presses against the fur garment or the fur skin as well as against the sawdust to rub the latter into the fur to insure thorough softening and cleaning of the fur. It is understood that when the drum 15 is rotated in the direction of the arrow shown in Figure 2 then a tumbling action is given to the fur garment or the fur skin as the ledges 17 tend to carry the garment or fur skin upward at the front of the drum and to drop the same downward when nearing a top position within the drum. Owing to the centrifugal force exerted by the revolving drum on the fur garment or skin the latter are thrown rearwardly and downwardly thereby dropping back on to the ledges 17 and the rim 18 of the drum in the rear of the revolving pressing and rubbing roller 60. From the foregoing it will be seen that by the arrangement described the fur garment or fur skin is continually subjected to a tumbling action within the barrel under the influence of the sawdust and also to a

rubbing and pressing action by the roller 60. It will also be noticed that by mounting the rubbing and pressing roller 60 in the manner described it is suspended within the drum 15 and is wholly independent of the rotary motion of the drum. It is understood that when the drum is rotating in the direction of the arrow shown in Figure 2, the roller 60 by being in contact with the fur garment or the fur skin is rotated and hence tends to soften the fur and to rub the sawdust into the same. In case the garment or fur skin lumps itself owing to the tumbling action, the roller 60 is liable to be carried upward a short distance in the direction of the rotation of the drum 15 until the lump is passed, after which the roller will return to its normal position in the lower portion of the drum 15. It is understood that in practice the rubbing and pressing roller is preferably formed of a shell of textile material filled with horsehair or other soft material.

After the softening and cleaning operation of the garment or fur skin has been completed then the tumbling drum 15 is stopped and the door 12 is opened to allow of opening the doors 21 and 31. When this has been done the door 12 is again closed and the drum 15 is rotated to allow the sawdust, dirt and loose hairs within the drum 15 to pass through the screens 25 and 32 into the casing 10 and thus freeing the garment and the fur skins of the sawdust and dirt. The sawdust, dirt and loose hair collect in a drawer 70 removably held in the bottom of the casing 10. The drawer 70 is provided at the open top with a removable screen 71 of a mesh to allow the sawdust and dirt to pass through into the drawer but to retain the loose hairs thus separating the same from the sawdust. After the sawdust, dirt and hair have passed out of the tumbling drum 15 then the latter is stopped and the door 12 is opened with the door openings 20 and 11 in register with each other. The screen 25 is now swung outward into open position, as shown in Figure 2, to allow removal of the garment or fur skin and to allow recharging of the drum with another garment or fur skin to be softened and cleaned next. The drawer 70 is removed from the casing 10 and then the screen 71 is lifted off to allow of freeing it of the loose hairs while the sawdust contained in the drawer 70 can be emptied from the latter and freed of the dirt for re-use in the drum 15. In order to properly guide the sawdust, dirt and hair discharged from the drum 15 to the drawer 70 use is preferably made of a deflecting plate or chute 72 arranged in the rear of the casing 10 and preferably concentric with the drum 15.

In order to permit applying the softening and cleaning device to be attached to a drum 15 of usual construction, as shown in

Figure 6, the links 63 are mounted on studs 80 riveted or otherwise attached to plates 81 fastened by bolts or other fastening devices 82 to the heads 16 of the drum.

5. It will be noticed that in refilling the drum 15 with sawdust, the drawer 70 (without the screen 71) is preferably used as a chute for doing so by placing the drawer in the door openings 11 and 20 at the time the drum is in 10 the position shown in Figure 2.

Having thus described my invention, I claim as new and desire to secure by Letters Patent:

1. In a fur softening and cleaning machine, a rotatable tumbling drum, a cushioned member, and suspension means suspending the said cushioned member within the drum in close proximity with the inner surface of the drum.
- 20 2. In a fur softening and cleaning machine, a rotatable tumbling drum, a cushion roller and suspension means on which the roller is journaled, the said suspension means being mounted to swing in the drum independent of the rotation thereof, the said suspension means supporting the roller in close proximity to the inner surface of the drum to coat with the same in softening a fur garment or fur skin.

- 30 3. In a fur softening and cleaning machine, a tumbling drum, a cushioned member adapted to press against the fur article to be softened, side arms carrying the said cushioned member and links on which the side arms are mounted to swing, the links being hung centrally in the tumbling drum.

- 40 4. In a fur softening and cleaning machine, a rotatable tumbling drum, a cushioned roller adapted to coat with the inner surface of the said tumbling drum, side arms in which the said roller is journaled, links pivotally connected with the said arms and provided with trunnions mounted to turn centrally in the said drum, the said links having stop pins and the said side arms being adapted to engage the said stop pins.

- 50 5. In a fur softening and cleaning machine, a tumbling drum adapted to contain a loose cleaning material and a rubbing device pivotally mounted within the said drum and adapted to engage and press the fur article to be softened and cleaned against the inner surface of the said tumbling drum, the said rubbing device rubbing the loose cleaning material into the fur during the tumbling of the fur article in the drum.

- 60 6. In a fur softening and cleaning machine, a casing provided with a door, a tumbling drum mounted to turn in the said casing and having a door adapted to register with the said casing door to allow of placing the fur article into the tumbling drum or to remove it therefrom, the said tumbling drum being adapted to contain a

loose cleaning material, and a rubbing device suspended within the said tumbling drum and coacting with the inner surface thereof and with the said loose cleaning material to soften and clean the fur article.

7. In a fur softening and cleaning machine, a casing provided with a door, a tumbling drum mounted to turn in the said casing and having a door adapted to register with the said casing door to allow of placing the fur article into the tumbling drum or to remove it therefrom, the said tumbling drum being adapted to contain a loose cleaning material, a rubbing device suspended within the said tumbling drum and coacting with the inner surface thereof and with the said loose cleaning material to soften and clean the fur article, and a screen mounted in the drum in register with the said drum door to allow the loose cleaning material, dirt and loose hairs to pass out of the drum into the casing.

8. In a fur softening and cleaning machine, a casing provided with a door, a tumbling drum mounted to turn in the said casing and having a door adapted to register with the said casing door to allow of placing the fur article into the tumbling drum or to remove it therefrom, the said tumbling drum being adapted to contain a loose cleaning material, a rubbing device suspended within the said tumbling drum and coacting with the inner surface thereof and with the said loose cleaning material to soften and clean the fur article, a screen mounted in the drum in register with the said drum door to allow the loose cleaning material, dirt and loose hairs to pass out of the drum into the casing, said casing having a drawer arranged in the bottom thereof adapted to receive the said cleaning material, dirt and hairs discharged from the drum.

9. In a fur softening and cleaning machine, a casing provided with a door, a tumbling drum mounted to turn in the said casing and having a door adapted to register with the said casing door to allow of placing the fur article into the tumbling drum or to remove it therefrom, the said tumbling drum being adapted to contain a loose cleaning material, a rubbing device suspended within the said tumbling drum and coacting with the inner surface thereof and with the said loose cleaning material to soften and clean the fur article, a screen mounted in the drum in register with the said drum door to allow the loose cleaning material, dirt and loose hairs to pass out of the drum into the casing, said casing being provided with a drawer arranged in the bottom thereof adapted to receive the said cleaning material, dirt and hairs discharged from the drum, the said drawer having a separating means for separating the cleaning material and the hairs.

10. In a fur softening and cleaning machine, a tumbling drum provided with a door and a screen in the door opening in the rear of the door.
5. 11. In a fur softening and cleaning machine, a tumbling drum provided with a door opening, and a sliding door on the outside and controlling the door opening and a screen hinged in the opening in the rear
10. of the door and adapted to swing outward through the door opening into open position at the time the said sliding door is in open position.
12. In a fur softening and cleaning machine, a tumbling drum provided with a door opening, a sliding door on the outside and controlling the door opening and a screen hinged in the door opening in the rear of the door and adapted to swing outward through the door opening into open position at the time the said sliding door is in open position, and a second door opening, sliding door and screen on the drum approximately diametrically opposite the said first-named door opening, a casing enclosing the said tumbling drum and a drawer in the bottom of the said casing.
15. 14. In a fur softening and cleaning machine, a revolute tumbling drum adapted to contain fur articles and provided at the inner surface with ledges and a rubbing device mounted to swing in the drum independent of the rotation thereof and adapted to coact with the said ledges to rub the fur articles as the latter pass between the rubbing device and the ledges.
20. 15. In a fur softening and cleaning machine, a casing enclosing a tumbling drum having means for discharging a loose cleaning material, dirt and hair therefrom, and a collecting receptacle for receiving the discharged cleaning material, dirt and hairs and having separating means for separating the loose cleaning material from the hair.
25. 13. In a fur softening and cleaning machine, a tumbling drum provided with a door opening, a sliding door on the outside and controlling the door opening and a

SAMUEL FRIEDMAN.
